UNITED STATES PATENT OFFICE.

ALLAN S. BARROWS, OF LOS ANGELES, CALIFORNIA.

CAR DOOR.

Application filed August 7, 1925. Serial No. 48,815.

This invention relates to improvements in car doors.

An object of the invention is to provide a car door for railway cars, wherein great strength against pressure in various directions is obtained, and more particularly to provide such a door of the outside sliding type so constructed and braced as to provide maximum strength.

10 A further object of the invention is to provide a car door construction comprising a main body portion in the form of a metallic sheet or sheets, with means for providing a tubular formation along the edge, 15 or edges, of the door, said means including stiffening elements, which may be of commercial form, secured adjacent an edge of the door sheet and extending at an angle thereto, in conjunction with other reinforcing elements secured to the outer extremities of the stiffening elements, and extending inwardly toward the door sheet and secured thereto in spaced relation with reference to the first mentioned stiffening elements.

20 A more specific object of the invention is to provide a tubular edge formation for a door body sheet in which the door sheet may be utilized as one wall of the tubular formation without the necessity for bending or otherwise shaping or forming the same, the remaining walls of the tubular formation being provided by the stiffening elements which are arranged and secured to the door sheet in a simple and effective manner.

25 Other objects and advantages of the invention will more clearly appear from the description and claims hereinafter following.

In the drawings forming a part of this specification, Figure 1 is a side elevational view of a portion of the car showing my improved door in connection therewith, the parts being broken away in order to better accommodate the figure on the sheet. Figure 2 is an enlarged, broken, horizontal, sectional view corresponding to the section line 2-2 of Figure 1. Figure 3 is an enlarged, 30 broken, vertical, sectional view corresponding to the section line 3-3 of Figure 1, and showing the application of the mounting rollers disposed within the tubular section at the edge of the door. Figure 4 is a partial vertical, sectional view similar to the lower portion of Figure 3, showing the ap-

plication of the door constructed in accordance with this invention in connection with mounting rollers secured to the car structure. Figure 5 is an enlarged, broken, horizontal, sectional view of a slightly different embodiment of the invention, said view being substantially similar to that shown in Figure 2. Figure 6 is a side elevational view of a portion of the car similar to Figure 1, and showing a slightly different embodiment of the invention. Figure 7 is an enlarged, broken, horizontal, sectional view corresponding to the section line 7-7 of Figure 6. Figure 8 is an enlarged, broken, vertical, sectional view corresponding to section line 8-8 of Figure 6. Figure 9 is an enlarged, vertical, sectional view similar to Figure 8 showing the door when utilized in connection with the so-called top hung type of mounting; and Figure 10 is an enlarged, broken, horizontal, sectional view, of another slightly different embodiment of the invention, such figure being of the same character as that illustrated in Figure 7.

35 Referring first to the construction illustrated in Figures 1 to 4 inclusive, 10 indicates the usual side wall of a box car, 11 the floor boards, 12 the car side sill, 13 the door posts or jambs at the front and rear ends of the door opening, and 14 indicates the lintel of the door frame.

40 In the arrangement illustrated in Figures 1 to 4 inclusive, a sliding outside door is shown designated generally by the reference character A. The door A comprises a main body portion, of a size and shape as to cover the door opening, and such body portion may consist of a single flat metallic panel or sheet, or a plurality of metallic panels or sheets as indicated in dotted lines, in the drawings, secured together by any suitable means to provide a rectangular formation, and such main body panel or sheet also may be provided with suitable strengthening elements inwardly of the edges thereof, if deemed desirable to thus strengthen the sheet in that portion within the reinforced edge construction as contemplated by my invention.

45 Secured to the top, bottom and forward marginal edges of the main body portion 15, of the door are reinforcing or stiffening elements in the form of Z-bars 19. Each of the Z-bars has one flange 20 secured to the main body portion of the door by means of countersunk rivets 21, all the flanges 20 being ar-

ranged so that the outer edges thereof coincide with the outer edges of the body portion of the door. Each of the Z-bars includes a web 22, which extends perpendicularly to the main body portion 15 of the door, and formed with the outer end of the web is an inwardly turned flange 23, extending in substantial parallelism with the body portion of the door. The Z-bars 19 are beveled at the corners of the door, as indicated at 24, and secured together in any suitable manner.

The rear marginal edge of the door panel 15 is provided with an inturned flange 26 to which is secured an angular member 27, by means of rivets 28 which are countersunk on the inner side of the flange 26, the intermediate portion 29 extending outwardly from the door plate 15 in a perpendicular direction, and being provided with an inturned flange 30 which is disposed in the same plane as the flanges 23 of the Z-bars. The angular member 27 is provided on the inner side of the flange 26 with an inturned flange 31 which in conjunction with the angular member 32 secured to the door post 13, functions as a spark or weather strip when the door is in operative position.

Secured to the outer flanges 23 of the Z-bars 19, and to the flange 30 of the angular member 27, by means of rivets 33, are the turned end portions 34 of bracing strips 35, each of said bracing strips being of suitable metallic construction and including an inclined web 36 which extends in an inward direction between the flanges 23 of the Z-bars and the flange 30 of the angle member 27, towards the door sheet 15, such reinforcing strips being provided with flanges 37 which are secured to the body portion of the door by means of rivets 38, the bracing strips 35 being identical in form, and having their ends beveled as indicated at 39' to provide a neat and efficient construction.

By the above described arrangement a plane metal sheet or panel or plurality of panels is provided with a tubular edge construction of great strength and rigidity, necessitating the use of a minimum of material, and providing a door which may be associated with mountings of an ordinary character, as will now be described.

The door may be utilized as the so-called top hung type, or as the so-called bottom hung type. In mounting the door as a bottom hung door, the usual track 39 may be provided which is secured to brackets 40 fastened to the side sill 12. With this construction rollers are usually mounted on the door proper, and in this connection a door constructed in accordance with the principles heretofore explained, lends itself to the application of rollers which operate upon the track 39. Disposed within the tubular edge formed by the bottom Z-bar 19 and

strip 35, and the adjacent portion of the door sheet at the bottom of the door are supporting brackets 41. Each of said brackets, carries a pin 42, upon which a roller 43 is mounted, such roller extending outwardly through a slot 44 in the web of the Z-bar 19 so as to bear upon the track 39, or if desired the tubular formation may be cut out at the point of application of the brackets 41, it being noted in either event that the flange 20 of the Z-bar and the adjacent marginal side of the door portion project behind the adjacent portion of the bracket 40 and the track 39 so as to limit the outward movement of the door when the same is operated. The top edge of the door 15 is formed by the flange 20 of the Z-bar 19, and the adjacent marginal edge of the portion 15, such edge projecting behind the flange portion 45 of the angular member 46 secured to the door frame by suitable rivets, thereby limiting the outward movement of the door, but permitting sliding movement thereof. The angle member 46' may be secured to the top of the door so as to be disposed outside of the flange 45 on the member 46 to provide means for limiting inward movement of the door. The forward edge of the door due to the disposition of the Z-bar provides a projecting flange portion adapted to be received between the door wear plate 47, and the cover strip 48. The angular member 27 at the rear edge of the door is provided with the inturned flange 31 providing a spark strip which co-operates with the angular member 32 secured to the adjacent door post 13.

If the door mounting is of a type wherein the rollers are carried by brackets secured to the car structure, it will be obvious that the disposition of the Z-bar and related members at the bottom edge of the door, permit the door to be used efficiently in connection with this type of mounting. As shown in Figure 4 the bracket 50 as shown is connected to the side sill 12, and each bracket 50 carries a roller 51. In this construction the door A is placed in position in the manner above described, the flange 20 of the Z-bar, and the adjacent bottom margin of the door extending behind the bracket 50, while the weight of the door is slidably supported upon the web 22 of the Z-bar, such Z-bar of course being braced by the reinforcing strip 35.

A slightly modified form of the invention is shown in Figure 5 of the drawing, this construction being identically similar with respect to that heretofore described, except for the arrangement of the rear edge portions of the door; all of such members therefore will be designated by the same reference characters heretofore used as designating similar parts. In the construction shown in Figure 5 instead of the angle mem-

ber 27 heretofore described, a Z-bar 60 is utilized, one flange 61 of which is secured to the rear edge of the door plate, the web of such Z-bar being disposed inwardly of the edge of the door portion 15, and extending perpendicularly outwardly from the door plate, and being provided with a flange 62 extending in substantial parallelism with the body portion of the door and to which the flange 34 of the bracing strip 35 is secured. A spark strip 63 is secured to the rear edge of the door, such spark strip including a flange which extends parallel with the flange 61 of the Z-bar, and including a flange 64 having an inwardly turned portion 65 adapted to co-operate with a suitable angle member 66 secured to the adjacent door post 13.

Referring to Figures 6 to 9 inclusive, another slightly different embodiment of the invention is illustrated. In this construction the main door sheet 100 may be of metal, and formed as a single sheet or panel, or made up of a plurality of sheets or panels suitably secured together, and such panel may be provided with a plurality of strengthening corrugations if desired. Secured to all four marginal edges of the panel 100 are Z-bars 101, each of such Z-bars including a flange 102 secured along the marginal edge of the door sheet 100, a web 103 extending perpendicularly to the main body sheet, and an outwardly turned flange 104 extending in substantial parallelism with the main body sheet 100, such flanges being secured to the body sheet by rivets 105, said Z-bars being beveled at 106 and secured together by any suitable means. Affixed to the inner faces of the flanges 104 of each of the Z-bars, is a reinforcing strip 107. Each of such strips comprises the flange portion 108 secured to the flange 104 of each Z-bar by suitable rivets which may be countersunk on their opposite sides, the flange 108 extending inwardly beyond the Z-bar a suitable distance and being provided with a web 109 preferably extending perpendicularly with reference to the main body sheet 100, the portions of the web 109 adjacent the body sheet being provided with a flange 110 which is secured to the body sheet by rivets 111. The rear edge of the door is provided with an angular member 112 having a turned portion 113 providing a spark strip adapted to co-operate with the angular member 114 secured to the door post 115. At the bottom of the door, as well as along its side and top edges, the Z-bars 101 and re-inforcing strips 108 provide a tubular member in which may be mounted the rollers 116, suitable brackets 117 being provided which fit within the tubular member and are secured therein, the rollers extending outwardly through the slots 118 in the web 101 of the Z-bar so as to rest upon the track 119.

carried by the brackets 120 secured to the side sill 112. The bottom and top flanges of the door provided by the flanges 104 and the reinforcing strips 108 project behind the brackets 120 at the bottom of the door, and behind the angular members 121 at the top of the door, the door being further provided at the top with an angular member 122 which limits inward movement of the door. The forward edge of the door provided by the flange 104, and the adjacent flange 108 of the reinforcing strips are arranged to extend between the wear plate 123 on the door member 115, and an angular cover strip secured to such door post. By this arrangement a door is provided which has great strength and necessitates the use of a minimum number of parts, the tubular edges of the door resulting in a great increase in strength.

In Figure 9 there is illustrated the door structure used as a top hung door. In this arrangement brackets 123 are secured to the top edge of the door, such brackets having rollers 124 mounted therein arranged to travel upon the track 125 secured to the door frame, it being noted that the flanges 104 of the adjacent Z-bar, and the flange 108 of the re-inforcing strip project behind the downturned end 126 of the track member, so as to limit the outward movement of the door and retain the same in operative position.

In Figure 10 there is illustrated another slightly different embodiment of the invention, the door sheet 200 being provided with Z-bars 201 along the top, bottom and front edges, such Z-bars and body member being connected by reinforcing strips 202 which include flanges 203 secured to the body portion 200 of the door by rivets 204, the web of the reinforcing strips 202 being inclined as shown. Each strip 202 is provided with a flange 205 which is securely connected to the adjacent flange of the Z-bar 201 as clearly shown in the drawings in Figure 10. To the edge of the door sheet 200 is secured by suitable rivets an angular member 206 having a flange 207 fastened to the door sheet 200 by rivets 208, the inner end portion of the member 206 being inwardly turned as indicated at 207 to provide a spark strip adapted to co-operate with the angular member 209 secured to the door post 209. A reinforcing strip 210 has one end portion 211 connected to the angular member 206 by means of rivets 212, such reinforcing strip being inclined outwardly and provided with a flange 213 secured to the door sheet 200 by means of rivets 214.

In the arrangements herein described an important purpose of my invention resides in providing the tubular formation along the edges of the door, in such manner that there is no necessity for bending or other-

wise shaping or forming the main body sheet of the door, the stiffening elements being so arranged that the main body portion of the sheet is utilized as part of the 5 tubular formation, the tubular formation bracing the edges of the door in various directions, and also providing a reinforced edge of a plurality of plies of material which make the door of such a character 10 that the same may be readily associated with mountings of the type ordinarily provided.

While I have herein shown and described what I now consider the preferred manner 15 of carrying out my invention, the same is merely illustrative and I contemplate all changes and modifications that come within the scope of the claims appended hereto.

I claim:

1. In a car door, the combination with a 20 door body portion; of means providing a tubular formation along one edge of said body portion, said means including a reinforcing member in the form of a commercial bar, secured to the body portion along the 25 edge thereof and extending at an angle to the plane of said portion, and an element in the form of a strip secured to said body portion inwardly of said member in spaced 30 relation thereto, said element extending at an angle to the plane of the body portion and connected with portions of said member remote from said body portion.
2. In a car door, the combination with a 35 door body portion; of a commercial angular rolled section secured along an edge of said door portion, said section extending at an angle to said door portion, and a reinforcing element of formed sheet metal secured to 40 said door body portion, inwardly of said rolled section, in spaced relation, and substantially parallel with respect thereto, said element being disposed at an angle to the door portion and connected with outer 45 free portions of said commercial rolled section.
3. In a car door, the combination with a 50 door body portion; of an angular commercial rolled section secured along an edge of said door portion, said section extending to one side of the plane of said door portion substantially at right angles thereto, and an element in the form of a strip secured to 55 said door portion, inwardly of said rolled section, in spaced relation and substantially parallel with respect thereto, said element extending to the same side of the plane of the body portion as said angular section, portions of said section and said element remote from the body portion being connected 60 together, one flange of said commercial section being extended to the opposite side

of the plane of the body portion of said door to provide a spark seal.

4. In a car door, the combination with a plurality of angular rolled reinforcing sections providing an articulated frame, including top, bottom and side members in the form of bars; a metallic body portion for said door having its edges secured to the surfaces of said sections at one side of said frame; and reinforcing elements in the form of strips, one of which is secured to said body portion inwardly of each of said frame sections and substantially parallel with respect thereto, said elements extending from said body portion at an angle thereto and each being connected with portions of the adjacent rolled section remote from the body portion of said door.

5. In a car door, the combination with a 80 main body portion; of an angular stiffening member in the form of a commercial bar, secured to said body portion and extending along an edge thereof, said stiffening member having a portion projecting to one side of the main plane of said body portion, substantially at right angles thereto; and a bracing element in the form of a strip secured to the main body portion in spaced relation with respect to said stiffening member, said bracing element also projecting to one side of the main plane of the body portion of the door, said bracing element and said stiffening member having portions thereof remote from said door connected together, the portion of the bracing element intermediate the body portion of said door and the extremities of said stiffening member being arranged diagonally to brace said stiffening element against rotation about its longitudinal axis.

6. In a door, the combination with a body portion; of a Z-bar extending along an edge of the body portion and having one flange thereof secured to the body portion, the web of said Z-bar being arranged substantially perpendicular to said body portion, and the other flange of said Z-bar overhanging said body portion; and a reinforcing element in the form of a strip, arranged in spaced relation with respect thereto and connected to the body portion of the door and to the overhanging flange of said Z-bar, the intermediate portion of said reinforcing element being arranged so as to lie upon a diverging angle from said overhanging flange toward said body portion.

In witness that I claim the foregoing I have hereunto subscribed my name this 28th day of July 1925.

ALLAN S. BARROWS.
